United States Patent Office.

CHARLES C. SAVERY, OF PHILADELPHIA, PENNSYLVANIA.

Design No. 3,473, dated May 4, 1869.

DESIGN FOR A TRADE-MARK.

The Schedule referred to in these Letters Patent and making part of the same

To all whom it may concern:

Be it known that I, CHARLES C. SAVERY, of the city and county of Philadelphia, and State of Pennsylvania, have invented a Design for a Trade-Mark; and I do hereby declare that the following is full and exact description thereof, reference being had to the accompanying drawing, representing the design.

The design is formed and stamped in a metallic plate, or of other suitable material.

The outline and configuration are, an oblong figure, with rounded ends, comprising each about two-thirds of a circle, more or less, and the intervening sides being rounded, or formed in the arc of a circle, as shown.

In the centre is a diamond-shaped aperture or figure. The title of the article which the trade-mark is to designate, is stamped on the plate.

Upon the plate, also, is stamped the name of the inventor, the dates of the patents by which the manufacture of the invention is protected, the manufacturers' names, or title, and their place of business.

The drawing shows my arrangement of all the words and figures stamped on the plate.

What I claim as my invention, and desire to secure by Letters Patent, is—

The design for a trade-mark, as herein specified and shown.

The above specification signed by me, this 20th day of February, 1869.

CHARLES C. SAVERY.
